PERFORATING IMPLEMENT HAVING MEANS TO ALIGN THE PUNCH AND DIE

Arthur K. Schott, Kenmore, N.Y., assignor to
George F. Wales, Kenmore, N.Y.

Application August 31, 1956, Serial No. 607,444

11 Claims. (Cl. 164—110)

This invention relates to a punching device for perforating sheet metal and other sheet material. More particularly, the invention relates to a self-contained punching device which is adapted to be mounted removably between the ram and the bed of a press to perforate a sheet upon actuation of the ram.

Self-contained perforating implements have come into widespread use because they permit punching a plurality of holes in sheet material simultaneously and in practically any desired relationship. These implements comprise a bodily-removable, manually-transportable support, a punch and a die mounted in axially-aligned relation in the support, and punch-stripping means. A plurality of these devices can be mounted between the bed and the ram of a press, so that upon actuation of the ram, the workpiece may be punched, notched, and/or otherwise perforated, in a plurality of places simultaneously.

Where a plurality of holes of non-circular configuration, such as triangular or rectangular holes, are to be punched simultaneously in a single work sheet, it has frequently not been convenient heretofore to use the same punch design for all the perforating implements if the apertures to be punched in the workpiece are not all similarly oriented. Thus, punch bits of the same rectangular design, together with the correspondingly shaped perforating dies, could be conveniently employed for punching rectangular holes simultaneously in a work sheet only where the holes to be punched in the work sheet were all oriented in the same manner relative to the work sheet. Where the holes were not so oriented, it has frequently proved necessary to provide punches having differently oriented bits and cooperating dies, thus adding to the cost of the equipment required and to the set-up time of the job.

Another drawback to conventional perforating implements has been the fact that occasionally the punch will jump out of the holder or support because of the force of stripping the punch from the work after a punching stroke. Means are provided in the conventional perforating implement for limiting the upward stripping movement of the punch, but when a punch dulls, it tends to stick in the work. The stripping spring then is required to exert greater pressure in order to strip the punch from the work, than when the punch is newly sharpened. Sometimes the punch suddenly lets go under the impulse of the stripping spring, the impact of the punch shears the screw or other stop means employed in the implement; and the punch goes flying out of the implement. Sometimes the operator strikes the work sheet or the punch with a mallet, when the punch sticks; and that causes the punch to let go suddenly and fly out of a perforating implement, impelled by the force of the stripping spring. If the operator does not notice that the punch is not in proper position in its unit, he may operate the punch again and fail to perforate a hole in a work sheet, or the punch may even get wedged in the press or in its own or another implement, and on the

2

next stroke of the press, the punch, or a perforating implement may be broken, or the work may be damaged.

An object of the present invention is to provide an improved self-contained punching implement in which a punch and the associated die are so mounted that a non-circular punch and die can readily be adjusted therein to permit optional shape direction of punch and die.

Another object of the invention is to provide an improved implement of the character described which will permit quick change of the punch and die so that a circular punch and associated die can readily be substituted for a shaped punch and die, or a punch and die of one shape can readily be substituted for a punch and die of another shape.

15 Another object of the invention is to provide an implement of the character described in which improved means is provided for limiting the upward movement of the punch under stripping force so that the punch cannot be thrown out of its guide sleeve by the stripping force.

20 A related object of the invention is to provide an improved means for retaining a punch in the guide sleeve of a self-contained perforating implement, in which any stripping force imparted to the punch and applied by the punch to the retaining means is absorbed thereby in 25 compression primarily, rather than as a shear force.

A related object of the invention is to provide an improved self-contained perforating implement in which means are provided to permit rapid and accurate positioning of the die and punching unit in the implement, 30 and disassembly thereof.

Another object of the invention is to provide an improved self-contained perforating implement which can be so made as to assure positive alignment of punch and die.

35 Still another object of the invention is to provide a perforating implement of the character described so constructed that the desired alignment of punch and die can be achieved with a single simultaneous, inexpensive machining operation.

40 Other objects of the invention are to provide improved guide means for keying the stripper sleeve to the holder, and an improved die retention device for securing the die readily and rapidly in the holder.

One embodiment of the invention is illustrated in the 45 drawings. In this embodiment the holder is of the conventional C-frame type, having a lower arm or base and an upper arm. A die is mounted in the lower arm of the implement, and a punching and stripping unit is mounted in alignment with the die in a guide opening 50 in the upper arm. The punching and stripping unit includes a guide sleeve slidably mounted in the guide opening of the upper arm and guided therein for reciprocal movement. The punch itself is reciprocably mounted and guided in the guide sleeve.

55 To allow for orientation of a shaped punch relative to the holder and the work sheet, duplicate key seats are provided in the punch, angularly spaced 90° apart, so that a key may be seated selectively in either seat for slidable engagement with a keyway on the interior surface of the guide sleeve. The punch may thus be readily mounted at two different positions 90° apart in the guide sleeve. The guide sleeve is slidably keyed to the holder by a key seated in the upper arm of the holder and slidable in an elongate keyway in the sleeve.

65 The punch is freely reciprocable in the guide sleeve over a limited distance. To limit the upward movement of the punch, and to prevent it from jumping out of the guide sleeve, a setscrew is threaded in the guide sleeve in a downwardly inclined direction. This set-screw engages in an elongate groove in the punch. It has a flat inner end perpendicular to its axis. The lower end of the groove is flatted off and is inclined at substantially

right angles to the axis of the set-screw, so that when the set-screw engages the flatted end of the groove the screw is put in compression instead of shear, and the punch is safely stopped without shearing the set-screw or jumping out of the guide sleeve. Threaded apertures angularly spaced 90° apart are provided in the guide sleeve so that the set-screw may be correctly positioned to restrict reciprocation of the punch.

The die assembly includes a button type die having a projecting stud on its undersurface. The stud is adapted to be inserted in a corresponding opening in the surface of the lower arm of the holder. This arm is split at its outer end to provide a split-clamp for receiving this stud. A screw is threaded in the arm to tighten the split clamp.

Proper alignment between the perforating die and the punching and stripping unit is assured by simultaneously machining keyways in the confronting faces of the upper and lower arms. Keys are seated in these slots to engage the die and sleeve respectively, to thus accurately align the die assembly with the punching and stripping unit. The key, which engages the sleeve, performs a second function, also, of guiding the sleeve in its axial reciprocating movement. It is U-shaped to engage in the two slots in the sleeve and in the holder and to be retained between the sleeve and the holder.

In the die duplicate key seats spaced 90° apart are provided so that the die may be rotated to be aligned with the punch.

The invention may be best understood by consideration of the appended detailed description, taken together with the drawings, in which:

Fig. 1 is a side elevation of one embodiment of a punching implement made according to this invention;

Fig. 2 is an end elevation thereof;

Fig. 3 is a top plan view thereof;

Fig. 4 is a section on line 4—4 of Fig. 1;

Fig. 5 is a partial axial section on an enlarged scale showing the punch in depressed position;

Fig. 6 is a side elevation of the guide sleeve;

Fig. 7 is a bottom view thereof;

Fig. 8 is a side elevation of one form of punch that may be used in the implement; and

Fig. 9 is a bottom view thereof.

Referring now in detail to the drawings, the self-contained perforating implement shown includes a C-frame holder 10 having a lower arm or base 11 and an upper arm 12. A punching and stripping assembly 15, including a guide sleeve 32, is mounted and guided for reciprocation in a guide opening 34 in the upper arm 12. A U-shaped feather key 50 is seated in the upper arm and is adapted to slide in a vertical keyway 52 in the guide sleeve. The key seat in the upper arm includes an elongate longitudinal slot 54 along the undersurface of the upper arm 12 which receives one leg of the U-shaped key 50; and an aperture 56 axially parallel with the elongate slot 54 and directed through the upper arm and opening into the guide opening 34 of the upper arm, in which aperture the other leg of the U-shaped key is seated.

A retainer disc 63 is mounted in a recess in the upper head and is secured thereto by a bolt 64, and engages in an elongate slot 66 extending axially of the guide sleeve. This slot 66 terminates at the lower end thereof in a shoulder 68.

The guide sleeve 32 has a collar 36 at its upper end which defines a shoulder at the upper end of the slot 66 as best seen in Figure 6. A lifter spring 48 is interposed between the collar 36 and the upper head, and constantly urges the guide sleeve to an inoperative position.

The punch has a cylindrical shank 40 reciprocably mounted in the guide sleeve. At its upper end, the punch has a flange 44 and a central boss 46 for engagement with the ram of a press, and at its lower end, the punch has a punch bit 38 which is a reduced extension of the cylindrical shank 40.

A set-screw 72 is threaded in an aperture 74 in the collar 36 of the guide sleeve in a downwardly inclined

direction. This set-screw engages in an elongate groove 76 extending axially of the punch and terminating in a lower shoulder 78 and an upper shoulder 78'. The set-screw has a flat inner end perpendicular to its axis. The lower shoulder 78 of the groove is flatted off and is inclined at substantially right angles to the axis of the set-screw, so that when the set-screw engages the flatted surface of the shoulder 78 the screw is put in compression instead of shear, and the punch is safely stopped, without shearing the set-screw or jumping out of the guide sleeve. The angle of inclination between the axis of the set-screw and the axis of the punch, in the preferred form of the invention illustrated in Fig. 5, is 75°.

Duplicate threaded apertures 74 and 74' are provided 15 in the collar 36 of the guide sleeve and are angularly displaced 90° from each other, as shown in Fig. 7.

To allow for orientation of a punch having a shaped bit 38 relative to the guide sleeve 34, the C-frame holder and the work sheet, duplicate Woodruff key seats 60 and 60' are provided on the outer surface of the punch, angularly spaced 90° apart, so that a Woodruff key 58 may be seated selectively in either seat for slidably engagement in a keyway 62 on the interior surface of the guide sleeve 34. The 90° angular spacing between the 25 threaded apertures 74 and 74' in the collar of the guide sleeve corresponds to the 90° spacing of the Woodruff key seats 60 and 60' in the cylindrical shank of the punch.

A heavy stripping spring 42 is interposed between the flange 44 of the punch and the collar 36 of the guide sleeve and serves to transmit motion of the punch to the guide sleeve until the sleeve has engaged the work, after which the stripping spring is compressed.

On the lower arm 11 the perforating die 14 is supported in alignment with the punch. The die is of generally cylindrical configuration and has an aperture 17 therein corresponding in cross-sectional shape to the cross-sectional shape of the punch, that is, to the shape of the hole to be punched in the work. A slug discharge chute 18 extends downwardly and outwardly from the aperture 17 through the die and to one side thereof. The die has a concentric cylindrical stud 16 (Fig. 5) protruding downwardly therefrom into a corresponding recess 18 in the arm 11. A transverse slit 20 in the lower arm intersects the axis of the aperture 18 and completely severs one half of the lower arm vertically, as best shown in Fig. 4, to form a split-clamp for securing the stud 16 in the arm 11. A screw 22 is threaded into the arm 11 traversing the opening 20 to operate this split clamp.

50 An L-shaped key 25 is inserted in a keyway 26 in the lower arm and a key recess 30 in the die. The key is pinned in position by a key retainer pin 28 which extends through aligned holes in the lower arm 11 and in the key 25. Duplicate key recesses 30 and 30' are 55 angularly spaced 90° apart in the die 14 so that the die may be securely positioned against rotation on the arm selectively in either of two angular positions which are spaced 90° apart. Thus, the die may be selectively positioned on the arm 11 to correspond to the position of the shaped punch bit 38 in the guide sleeve 34 in the upper arm.

60 The elongate keyways 26 and 54 extending longitudinally of the holder 10 on the confronting faces of the two arms are aligned, to facilitate and insure alignment 65 of the punch and die. Alignment of the two keyways is assured by the simultaneous machining of the keyways.

The punching and stripping unit 15 and the perforating die 14 with its stud 16 are coaxial with a conventional pilot pin 82 projecting downwardly from the undersurface of the lower arm 11. As is conventional, the lower arm 11 and the upper arm 12 are longitudinally slotted for convenience in securing the holder on a support between the bed and ram of a press.

In the operation of the device, after it has been positioned between the bed and ram of a press, for example,

the boss 46 of the punch is engaged by the ram and is forced down toward and through the work. As the punch is forced downwardly, the heavy stripping spring 42 moves the guide sleeve down until it engages the work, compressing the lifter spring 48. When the guide sleeve engages the work, the punch continues to move down under the force of the ram, compressing the stripping spring, causing the punch bit 38 to penetrate the work and perforate it, and forcing the slug through the shaped aperture 17 from which it drops down through the discharge chute 18.

As the ram moves upwardly, the stripping spring 42 expands and strips the punch bit 38 from the work and moves the punch vertically upward through the guide sleeve. The lifter spring 48 then returns the guide sleeve to a desired inoperative position in the upper arm, as illustrated in Fig. 1.

During the stripping operation, the upward movement of the punch is limited by the engagement of the set-screw 72 in the groove 76. Because the set-screw has a flat inner end which makes flush contact with the inclined lower shoulder 78 of the groove, and because the axis of the set-screw is inclined downwardly, any force transmitted to the set-screw by the punch is absorbed by the screw in compression instead of shear, so that the punch is safely stopped without shearing the set-screw and without jumping out of the guide sleeve.

To limit the upward movement of the guide sleeve, and to prevent it from falling out of the holder, particularly when the holder is being transported from one place to another, the retainer 63 is engaged in the slot 66 on the outer surface of the guide sleeve. Usually, the forces involved are not great.

As the punch reciprocates in the guide sleeve, the Woodruff key 58 slides in the keyway 62 in the guide sleeve and insures that there is no relative angular movement between the punch and the guide sleeve. At the same time, the Woodruff key guides the punch in its axial reciprocating movement. The U-shaped key 50 similarly slides in the keyway 52 in the guide sleeve and prevents relative angular movement between the guide sleeve and the upper arm of the holder, while guiding the sleeve in its axial reciprocating movement in the upper arm. Thus, the shaped punch bit 38 is maintained in a specific orientation relative to the holder by the Woodruff key which is interposed between the punch and the guide sleeve, and by the U-shaped key which is interposed between the guide sleeve and the holder.

The die 14 is oriented properly by placing the L-shaped key 25 in either of the key recesses 30 and 30' of the die.

Where the punch bit 38 is non-circular in shape, having, for example, the configurations shown in Fig. 9, it may be desirable to orient the punch bits of two or more adjacent perforating implements by orientation of the punch relative to the work, rather than by orientation of the holder relative to the work. With the perforating implement of this invention, this orientation is readily accomplished by withdrawing the punch from the guide sleeve. To do this, the set-screw 72 is withdrawn from engagement with the groove 76 and the Woodruff key is then removed from its original seat and is placed in the second seat, which is angularly spaced 90° from the original seat. The punch is then replaced, with the Woodruff key sliding in its keyway. The set-screw 72 is then replaced in the second threaded aperture 74', which is spaced 90° from the original aperture to correspond with the angular displacement between the seats for the Woodruff key. Thus, the punch bit 38 may be oriented through a 90° angle, and in its new position, it is held against angular movement relative to the holder by the engagement of the Woodruff key with the keyway in the guide sleeve.

The die 14 may be similarly oriented by a withdrawal of the key retainer pin 28, removal of the L-shaped key 25 from its recess 30, rotation of the die through a 90°

angle, and placement of the L-shaped key 25 in the second keyway 30'. After placement in the second key recess 30', the L-shaped key is pinned in position by the key retainer pin 28. To rotate the die relative to the lower arm 11, it is necessary to ease the bolt 22 in the split-clamp. As used in the specification and claims, the terms "shaped punch" and "shaped die" refer to such elements as are used to produce non-circular openings in the work-piece.

While the invention has been described in connection with a specific embodiment thereof, it will be understood that it is capable of further modification, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth, and as fall within the scope of the invention or the limits of the appended claims.

Having thus described my invention what I claim is:

1. A self-contained punching apparatus for use between the bed and ram of a press comprising a holder having a lower base and an arm over said base, a shaped die mounted on said base, a punching and stripping assembly including a guide sleeve reciprocably mounted and guided in a guide opening in said arm, a punch having a cylindrical shank and a shaped bit, said shank being reciprocably mounted and guided in said guide sleeve with said shaped bit in alignment with said die, and a key seated in said punch and adapted to slide in a keyway in said guide sleeve, said punch having two key seats angularly displaced from each other and each adapted to receive and seat said key, whereby said punch may be selectively positioned relative to said guide sleeve in either of two fixed angular positions for cooperation with a die of like shape which can be correspondingly selectively positioned, said punch having a peripheral axially extending recess, a set-screw seated in a threaded aperture in said reciprocably movable guide sleeve and engaging in said recess, said sleeve having two threaded apertures each adapted to receive said set-screw and angularly spaced apart corresponding to the spacing of said key seats, whereby the reciprocal outward movement of said punch in said guide sleeve is limited in each angular position of said punch in said guide sleeve.

2. A self-contained punching apparatus for use between the bed and ram of a press comprising a holder having a lower base and an arm over said base, a die mounted on said base, a punching and stripping assembly including a guide sleeve reciprocably mounted and guided in a guide opening in said arm, and a punch reciprocably mounted and guided in said guide sleeve in alignment with said die, said punch having a peripheral, axially-extending recess terminating at each end thereof in a shoulder, a set-screw threaded through an aperture in said reciprocably movable guide sleeve and protruding therefrom toward said recess and between said shoulders to engage one of said shoulders to limit the outward reciprocal movement of said punch relative to said guide sleeve, the axis of said set-screw being inclined downwardly toward the axis of the punch and making an acute angle therewith.

3. A self-contained punching apparatus for use between the bed and ram of a press comprising a holder having a lower base and an arm over said base, a die mounted on said base, a punching and stripping assembly including a guide sleeve reciprocably mounted and guided in a guide opening in said arm, a punch reciprocably mounted and guided in said guide sleeve in alignment with said die, stripping spring means interposed between said punch and guide sleeve adapted to return said punch to an initial position spaced from said die, said punch having a peripheral, axially-extending recess, the lower end of which is inclined at an obtuse angle to the axis of the punch, and a screw projecting through an aperture in said recipro-

cably movable guide sleeve toward said recess and having a flat end surface, the axis of said screw being inclined downwardly toward the axis of said punch at an acute angle therewith, the said lower end of said recess being inclined for flush engagement with the flat end surface of said screw.

4. The punching apparatus of claim 3 wherein the acute angle between the axis of said set-screw and the axis of said punch is 75°.

5. The punching apparatus of claim 3 including feather key means carried by said arm and interposed between said reciprocably movable guide sleeve and arm to limit angular movement therebetween.

6. The punching apparatus of claim 3 including means to limit reciprocal movement of said sleeve in the upper head of said holder, said means comprising a rigid retainer disk removably carried by said arm and extending into an elongate slot in said guide sleeve.

7. A self-contained punching apparatus for use between the bed and ram of a press comprising a holder having a lower base and an arm over said base, a shaped die mounted on said base, a punching and stripping assembly of cylindrical configuration and including a guide sleeve reciprocably mounted and guided in a guide opening in said arm, a shaped punch reciprocably mounted and guided in said guide sleeve in alignment with said die, first feather key means interposed between said guide sleeve and arm adapted to prevent relative angular movement therebetween, second feather key means interposed between said punch and guide sleeve adapted to prevent relative angular movement therebetween, first means angularly disposed with respect to said key means and detachably secured to said arm and adapted to limit reciprocal movement of said guide sleeve in said arm, and second means angularly disposed with respect to said key means and removably secured to said guide sleeve adapted to restrict reciprocal movement of said punch therein.

8. A self-contained punching apparatus for use between the bed and ram of a press and comprising a stationary C-frame having a fixed upper arm and a lower arm, a single shaped die removably and nestingly mounted on said lower arm, a sleeve reciprocably mounted in a bore in said upper arm, a punch reciprocable in said sleeve, a single straight slot in the upper side of the lower arm, a registering slot in the lower side of the upper arm, said slots extending radially of the axis of the bore in said upper arm, and stationary keys in said slots to key said die and reciprocable sleeve to the C-frame to align said sleeve angularly with said die about their axes.

9. A self-contained punching apparatus for use between the bed and ram of a press and comprising a stationary C-frame having a fixed upper arm and a lower arm, a single shaped die removably and nestingly mounted on said lower arm, a sleeve reciprocably mounted in a bore in said upper arm, a punch reciprocable in said sleeve, a single straight slot in the upper side of the lower arm, a registering slot in the lower side of the upper arm, said slots extending radially of the axis of the bore in said upper arm, slots in said sleeve and die in registry with the slots in said arms, and stationary keys in said slots to key said die and reciprocable sleeve to the C-frame to align said sleeve angularly with said die about their axes.

10. A self-contained punching apparatus for use between the bed and ram of a press, comprising a station-

ary holder having a fixed upper arm and a lower arm, a single shaped die detachably and nestingly mounted on said lower arm, a sleeve reciprocably mounted and guided in a bore in said upper arm, a punch reciprocable in said sleeve, a single straight slot in the upper side of the lower arm, a registering slot in the lower side of the upper arm, said slots extending radially of the axis of the bore in said upper arm, slots in said sleeve and die in registry with the slots in said arms, stationary keys seated in said slots to key said die and reciprocable sleeve to the C-frame to align said sleeve angularly with said die about their axes, and a key seated in said punch and adapted to slide in a keyway in said sleeve, said punch having two key seats angularly displaced by 90° each adapted to receive and seat said key whereby said punch may be selectively angularly positioned relative to said sleeve and said C-frame, said punch having a peripheral, axially extending recess defining a shoulder, a set-screw rigidly carried in a threaded aperture in said guide sleeve and having an end projecting toward said punch and engaged in said recess, said sleeve having two threaded apertures each adapted to receive said set-screw and angularly displaced by 90° to correspond to the spacing of the seats for the key, whereby the reciprocal movement of said punch in said reciprocably mounted sleeve is limited in each placement of said punch in said sleeve in one direction by engagement of said screw with said shoulder.

11. A self-contained punching apparatus for use between the bed and ram of a press comprising a holder having a lower base and an arm over said base, a shaped die mounted on said base, a punching and stripping assembly including a guide sleeve reciprocably mounted in a guide opening in said arm, said arm having a key slot directed transversely of said opening and facing said base, said arm also having an aperture vertically spaced from said slot and communicating with said opening and aligned with said slot, a shaped punch reciprocably mounted and guided in said guide sleeve in alignment with said die, and U-shaped key means having a leg snugly carried by said arm in said slot and a second leg loosely received in said aperture, said key being interposed between said arm and said guide sleeve for snug engagement in a slot in said guide sleeve to prevent relative angular movement therebetween.
